UNITED STATES PATENT OFFICE.

GEORGE W. CORSEPINS, OF DOWNEY, IDAHO.

WIRE-STRETCHER.

1,244,836.

Specification of Letters Patent. Patented Oct. 30, 1917.

Application filed March 30, 1917. Serial No. 158,577.

To all whom it may concern:

Be it known that I, GEORGE W. CORSEPINS, a citizen of the United States, residing at Downey, in the county of Bannock and State of Idaho, have invented certain new and useful Improvements in Wire-Stretchers, of which the following is a specification.

The present invention relates to new and useful improvements in wire stretchers.

10 An object of the invention is the provision of a wire stretcher which can be applied to a post of usual construction and can be so operated as to tighten the wire whereby it can be stretched and tacked to the post in 15 said tightened or stretched position.

Another object of the invention is the provision of a stretcher which may be used as a wire tightener in the middle of a fence and left there in position so the wire may be 20 stretched at any future time. For this reason the crank is detachable making it possible to have two or more stretchers and only one crank.

Another object of the invention is the provision of a pivoted means for engaging the post and locking the wire against loosening after it has been stretched to the desired tension.

30 A further object of the invention is to improve and simplify wire stretchers, rendering them comparatively simple and inexpensive to manufacture, reliable and efficient in use, and readily operated, it being understood in this connection that various minor changes 35 in the specific details of construction can be resorted to within the scope of the appended claims, without departing from the spirit or claims, without departing from the spirit or sacrificing any of the advantages of the invention.

40 In the accompanying drawings forming a part of the present application;

Figure 1 is an end view of the wire stretcher;

Fig. 2 is a side view thereof;

Fig. 3 is a plan view thereof;

Fig. 4 is a detail perspective view of the bar;

Fig. 5 is a detail perspective view of the operating crank, and

50 Fig. 6 is a detail sectional view showing the locking arm.

Referring to the accompanying drawings

by corresponding characters of reference throughout the several views, the numeral 7 designates a post to which the wire 8 is to 55 be fastened after it is stretched to the desired tension.

The wire stretcher is shown in general at 9 and consists of a body or bar 10 having a slot 11 formed therein with an offset end 60 opening 12 through which the wire to be stretched is inserted into the slot 11. One end of the bar 10 is notched as at 13 and in this notch is pivoted a locking arm 14 adapted when in the dotted line positions 65 shown in Figs. 2 and 6 to permit the rotation of the bar 10 by a suitable operating crank 15 and when in the full line position shown in these two figures, to lock the bar 10 against rotation.

70 A suitable shoulder 16 is provided at the lower end of the notch 13 which limits the outward movement of the arm 14 preventing it from becoming engaged with the post 7 during the operation of the device.

75 In use the bar 10 is placed with one side against the post and the wire stretched across the latter and is brought into engagement with the notch 11. As the bar 10 is rotated the wire 8 will be wound upon the 80 bar 10 until it reaches a sufficient tension after which it is tacked to the post 7 and the wire then disengaged from the notch or slot 11 permitting the device to be removed 85 and positioned adjacent the next desired post.

90 From the foregoing description taken in connection with the accompanying drawings it will be manifest that a wire stretcher is provided which will fulfil all of the necessary requirements of such a device.

Having thus fully described the invention what I claim to be new and desire to protect by Letters Patent is:

95 1. In a wire stretcher, the combination of a rotatable bar, having a slot therein for receiving a strand of wire, a detachable crank for rotating said bar, and an arm pivoted to the end of said bar for locking the same against rotation.

100 2. The combination in a wire stretcher, of a rotatable bar adapted to engage one side of a fastened post, a slot formed in said bar for receiving a strand of wire, a notch open-

ing from said slot through the side of the bar and permitting the insertion of the strand of wire thereinto, a detachable crank adapted to engage one end of the bar for 5 rotating the latter, a pivoted arm attached to one end of the bar and adapted to be swung into the path of the post for engagement therewith and locking the bar

against rotation, and means for limiting the outward movement of said arm.

In testimony whereof I affix my signature, 10 in the presence of two witnesses.

G. W. CORSEPINS.

Witnesses:

FRED WAITE,
CHESTER OWEN.
